UNITED STATES PATENT OFFICE.

JOHN W. IMLER AND DANIEL W. SNOWDEN, OF IMLERTOWN, PA.

STRAW-STACKER CARRIAGE.

SPECIFICATION forming part of Letters Patent No. 291,350, dated January 1, 1884.

Application filed October 30, 1883. (No model.)

To all whom it may concern:

Be it known that we, J. W. IMLER and D. W. SNOWDEN, citizens of the United States, residing at Imlertown, in the county of Bedford and State of Pennsylvania, have invented certain new and useful Improvements in Straw-Stacker Carriages; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of a plan view of the invention. Fig. 2 is a front elevation, and Fig. 3 is a vertical transverse sectional view.

This invention has relation to straw-stacker carriages; and it consists in the construction and novel arrangement of devices, as will be hereinafter fully described, and particularly pointed out in the claim appended.

20 Referring by letter to the accompanying drawings, *a* designates the main carriage-frame, which is adapted to be connected to the rear end of the thrashing-machine in any suitable manner.

25 Upon the main frame *a* is mounted an auxiliary revolving and sliding frame, *b*. The rear cross-timber, *c*, of the main frame is provided in its upper face with an annular base-plate, *d*, having a central opening, *e*. This base-plate *d* is let into a recess, *e'*, in the cross-timber *c*.

30 Upon the base-plate *d* an annular top plate, *f*, rests and revolves. This top plate *f* also has a central opening, *g*, and is secured in a recess, *g'*, in the under face of the bed-plate *h* of the revolving frame *b*. The top plate *i* of the revolving frame *b* is slotted through longitudinally and vertically at its middle for nearly its entire length, as shown at *i'*, and it is held upon the bed-plate *h* by guide-clamps 35 *k k'*, which permit it to slide endwise on said bed-plate, so that the straw-carrier may be moved to avoid a post in the barn or mow. A shaft, *l*, passes through the central openings in the base-plate *d* and top plate *f*, and is

provided at each end with a miter-gear wheel, 50 *m m'*. The guide-clamp *k'* is provided with a bearing, *n*, for a hollow pinion, *o*, which meshes with the upper miter-gear, *m'*. A grooved shaft, *p*, having a bearing, *p'*, at one end of the top plate *f*, slides through the hollow pinion *o*, and a screw, *q*, in the sleeve *o'* of the pinion *o* enters the groove *r* of the shaft *p*, and causes the pinion to revolve with the shaft *p*, which is provided with a band-wheel, 55 *s*, on its outer end.

60 *t t'* designate the bearings for the lower carrier-shaft, which is provided at one end with a band-wheel, *s'*, which is connected with the band-wheel *s* by a belt or chain. The rear cross-timber of the main frame is provided on its under face with hangers *u u*, which furnish bearings for the shaft *v*, provided with the pinion *w*, which meshes with the miter-gear *m*, and the band-wheel *x*, which receives the belt from the thrashing-machine. By 65 this construction we are enabled to deliver the straw at any fractional part of three-fourths of a circle by revolving the auxiliary frame, and we may avoid a post in the barn or mow by sliding the top plate *i* on the bed-plate *h*, which moves the straw-carrier to one side without disengaging the gearing.

70 Having thus fully described our invention, what we claim as new, and desire to secure by Letters Patent, is—

75 In a straw-stacker carriage, the combination of the bed-plate, the revolving frame pivoted thereon, a sliding top plate, guide-clamp connecting it to the bed-plate and formed with a shaft-bearing, a grooved sliding 80 shaft, a bevel-pinion on said shaft, the bevel-gear wheel *m*, and pivot-shaft *t*, whereby the sliding top plate may be shifted to move the straw-carrier on said sliding top plate without disengaging the gearing, substantially as 85 90 specified.

In testimony whereof we affix our signatures in presence of two witnesses.

J. W. IMLER.
D. W. SNOWDEN.
